FIG-5

UNITED STATES PATENT OFFICE

2,353,350

ACTUATING MEANS

Carl H. Millerwise, Detroit, Mich., assignor to Detroit Lubricator Company, Detroit, Mich., a corporation of Michigan

Application September 14, 1942, Serial No. 458,207

6 Claims. (Cl. 60—23)

This invention relates to new and useful improvements in actuating means and more particularly to a thermostatic operating device.

An object of the invention is to provide means to compensate for variation in the heat input to an electrically energized heat motor.

Another object is to provide means to reduce the time lag of operation of the heat motor upon deenergization of the heating means.

The invention consists in the improved construction and the novel combination of parts to be more fully described hereinafter, and the novelty of which will be particularly pointed out and distinctly claimed.

In the accompanying drawing, to be taken as a part of this specification, there is fully and clearly illustrated a preferred embodiment of the invention, in which drawing:

Figure 1 is a view in side elevation and partly in vertical section of the operating device as applied to a flow controlling valve;

Fig. 2 is a plan view in section on the line 2—2 of Fig. 1;

Fig. 3 is a detail view in prospective of a heating element;

Fig. 4 is a detail view in side elevation showing the energized position of the operating device, and

Fig. 5 is a detail view in section on the line 5—5 of Fig. 2.

Referring to the drawing by characters of reference, 1 designates generally a valve having a casing with a flow passageway therethrough controlled by a valve member 2 having a longitudinally reciprocal stem 3 which extends upward through a valve bonnet 4 and is guided at its upper end in a guide member 5. Supported on the bonnet 4 and surrounding the stem 3, there is a permanent magnet 6 of annular form which is secured to the bonnet 4 by welding, or the like. Carried about and rigidly fixed on the stem 3 between the magnet 6 and the guide member 5, there is an armature 7 cooperable with the magnet 6 and formed by the lower annular flange of a collar member 8 having an upper annular flange 9. Also mounted on the bonnet 4, there is a housing 10 which encloses the valve superstructure and which has a removable cover member 11.

Also positioned within the housing 10, there is a thermostatic operating device 12 carried by the housing or end wall 13. Secured to the wall 13, there is a horizontal bracket or supporting member 14 having horizontally spaced and vertically positioned yolk type supporting arms 15

which receive and journal the end trunnions 16 of a horizontally positioned, rectangular supporting bar or member 17. Secured to the bottom face of the bar 17, and extending therefrom toward the collar 8, there is an electrically energized thermostatic heat motor 18 having a bimetal operating element 19, preferably a flat plate of substantially truncated triangular form tapering toward the stem 3 and having an end slot to provide arms 20, 21 which can bear upward at substantially diametrically opposite points against the under face of flange 9. The arm 21 has a downturned or directed end extension 22 engageable with the top face of armature flange 7. Secured tightly to the underface of the bimetal element 19, there is an electric resistance heating element 23, see Fig. 3, faced by top and bottom sheets of electric insulating material 24, 25 respectively, such as mica. The heating means 23 comprises an electrical resistance coil 26 wound in zig zag form on the upper face of an insulating sheet 27, preferably of mica. The element 23 and the sheets 24, 25 are of truncated triangular form to conform to the bimetal element 19 and are secured to the bar 17 and at their outer end are held by clips 28 to the element 19. Secured to and extending from the top face of the bar 17, there is a thermostatic compensating element 29, preferably a flat bimetal plate of truncated triangular form having an end slot 30 in its free end to receive an adjustment screw 31 with an upward facing flange 32 on which the free end of the element 29 seats at diametrically opposite points.

35 Positioned between the element 29 and the bar 17, there is a sheet metal heat-conducting member 33 of truncated triangular form which is bent downward, as at 34, for substantially half the distance between the elements 19 and 29 and is then curved convexly downward toward the element 19 to lie adjacent, but in spaced relation thereto, as at 35. The elements 19 and 29 and the conducting member 33 are secured to the bar 17 by heat conducting nuts and bolts 36. The heating element 23 and the insulating sheets 24, 25 are secured to the bar 17 by screws 36a which extend through apertures 37 in the coil sheet 27 to provide binding posts for the ends of coil 26 and to which the lead wires 38, 39 are secured. The heat conducting member 33 is preferably of hard copper and of about .005" thickness, so that it exerts a relatively slight resistance to upward movement of the element 19 upon engagement of the element 19 therewith.

50 Operation of the operating device 12, as ap-

plied to the valve of Fig. 1, is as follows. Adjustment of the screw 31 to move the flange 32 downward will increase the time period after energization of heat motor 18, which is required to move the valve to open position, and will also provide a shorter closing time after deenergization of coil 26. Should the ambient temperature within the housing 10 increase, then the compensating element 29 will bow or warp convexly downward so as to compensate for the convexly downward bowing or warping of the element 19, which bowing of element 19 would otherwise tend to move the valve toward open position. When the circuit is closed through lead wires 38, 39 to energize coil 26 and impart heat to the element 19, the element 19 will tend to bow upward at its flange engaging portions 20, 21 and when the potential force has increased sufficiently to overcome the magnet 6, then the valve member 2 will be moved quickly toward open position, bringing the element 19 into engagement with the heat conducting member 33. When the valve has moved to full open position, the element 29 will compensate for increase in ambient temperature within the housing 10 and also, by radiation and conduction through the screws 36 and the member 33, will compensate for any variation in heat imparted to the element 19 such as would result from voltage fluctuation. This compensation will rock the bar 17 counterclockwise facing Fig. 1 so that the force of the element 19 acting to hold the valve in full open position will remain substantially constant irrespective of continued heating of the element 19. The member 33 serves to dissipate heat from the element 19 both by conduction of heat from the element 19 to the compensating element 29 and also by radiation from the surface of the member 33. The heat transfer from the element 19 to the member 33, of which a part is conducted to the element 29, serves to completely compensate for temperature increase of the element 19 and to maintain the tension of the element 19 such that upon breaking of circuit through lead wires 38, 39 and deenergization of coil 26, the free end of the element 19 will substantially immediately move downward with consequent movement of the valve member 2 toward closed position. Not only does the member 33 enhance the compensation afforded by the element 29, but it also, during downward movement of the element 19 after deenergization of coil 26, serves to increase the cooling rate of the element 19 by dissipation of heat therefrom. It will be noted that the member 33 by its spacing from the element 19 in the deenergized and cold position of the device 12 does not abstract heat from the element 19 until the element has started to move the valve toward open position, and until sufficient heat has been stored in the element 19 to assure its operation with a minimum time lag. It will, of course, be understood that the element 29 will bow convexly upward, thereby rotating the bar 17 clockwise facing Fig. 1, should there be a drop in ambient temperature which would cause the element 19 to bow downward at its flange engaging end portions 20, 21, thereby to hold the end portions 20, 21 in contact with the flange 9.

What is claimed and is desired to be secured by Letters Patent of the United States is:

1. An automatic actuator comprising a control device, a bimetal operating element for moving said device, electric heating means for said element, a movable supporting member for said element, a bimetal compensating element operable

to move said supporting member to change the position of said operating element relative to said device, and a heat conducting member operable to transmit heat to said compensating element 5 from said operating element, said conducting member being spaced from one of said elements and engaged with the other of said elements and being engageable with said one element upon movement of said operating element thereby to control the movement of said device by said operating element by conduction of heat from said operating element to said compensating element.

2. An automatic actuator comprising a control device, a bimetal operating element for moving said device, electric heating means for said element, a movable supporting member for said element, a bimetal compensating element operable to move said supporting member to change the position of said operating element relative to 20 said device, and a heat conducting member extending from said compensating element, said conducting member being spaced from and in the path of movement of said operating element for engagement therewith, thereby to control the 25 movement of said device by said operating element by conduction of heat to said compensating element.

3. An automatic actuator comprising a control device, a bimetal operating element for moving said device, electric heating means for said element, a movable supporting member for said element, a bimetal compensating element operable to move said supporting member to change the position of said operating element relative to 30 said device, and a resilient heat conducting member extending from said compensating element, said conducting member being spaced from and in the path of movement of said operating element for engagement therewith and movement 35 therewith, thereby to control the movement of said device by said operating element by conduction of heat to said compensating element.

4. An automatic actuator comprising a movable supporting member, a bimetal operating element 45 extending from said member, an electric heating means for said element, a bimetal compensating element extending from said member, a heat conducting member in contact with said compensating element and extending from said 50 supporting member into the path of movement of said operating element, and means securing said elements and said conducting member to said supporting member so that said compensating element is operable to move said supporting member to change the position of said compensating element.

5. An automatic actuator comprising a movable supporting member, a thermostatic element secured to said member, heating means for said element, a thermostatic element operable to move 60 said supporting member to change the position of said first-named thermostatic element, a heat conducting member for transmitting heat to said second-named thermostatic element, said heat 65 conducting member having a portion in the path of movement of and spaced from said first-named thermostatic element, said heat conducting member upon contact by said first-named thermostatic element transmitting heat from said first-named to said second-named thermostatic element thereby to change the movement of said first-named thermostatic element in response to the heat imparted thereto by said heating means 70 and to change the position of said supporting member.

6. An automatic actuator comprising a supporting bar journaled for movement about its longitudinal axis, a flat bimetal operating element seating at one end against one face of said bar, a flat bimetal compensating element overlying said operating element and seating at one end against an opposite face of said bar, a resilient heat conducting member having one end interposed between said compensating element and said opposite face and extending between said elements, the free end of said conducting member

10 being spaced from and in the path of movement of said operating element, an electric heating element secured in intimate heat exchange relation to said operating element, means securing said elements and said conducting member to said bar, and means supporting the free end of said compensating element so that warping of said compensating element will change the position of the free end of said operating element.
